Inventor:
Aubrey W. Seels,
By Myself, Lee, Chatta, Miles,
Attest,

Patented May 10, 1927.

UNITED STATES PATENT OFFICE.

AUBREY W. SEELS, OF CHICAGO, ILLINOIS, ASSIGNOR TO CHICAGO BRIDGE & IRON COMPANY, OF CHICAGO, ILLINOIS, A CORPORATION OF ILLINOIS.

CROWN SUPPORT FOR GAS HOLDERS.

Application filed October 2, 1925. Serial No. 60,059.

This invention relates to improvements in crown supports for gas holders; and more especially to a crown support for gas holders of the type having two or more telescoping sections, in which the center member rises and falls in relation to the amount of gas contained in the holder.

In the construction of such gas holders it is necessary to provide a support for the crown or roof when the holder is empty or deflated. When the crown or roof is raised by the gas inside, however, no such support is needed; as in such case the crown or roof will be supported by the gas itself. Heretofore, difficulty has been encountered in properly taking care of the weight of the crown support itself when the crown is raised by the gas inside. I have overcome this difficulty in a simple manner as will be explained more in detail hereinafter.

Other features and advantages of my invention will appear more fully as I proceed with my specification.

In that form of device embodying the features of my invention, and shown in the accompanying drawings, Figure 1 is a vertical sectional view of a gas holder showing my improved crown support, and Fig. 2 is a top plan view of the same with the crown or roof of the gas holder removed.

As shown in the drawings, 10 indicates the central telescoping member or inner lift or bell of a gas holder of a well known form and construction, the top of which is closed by the roof or crown 11. In Fig. 1, such roof or crown 11 is shown in an elevated position in solid lines and indicated by the broken lines in the position it occupies when the holder is empty or deflated. When in the latter position, some means must be provided for supporting the crown 11.

The supporting means referred to comprise a series of radial trusses, beams, or other suitable structural members indicated in general by 12, 12, and comprising the upper chords 12^a, the lower chords 12^b, the diagonal struts or braces 12^c and the vertical braces or bars 12^d. The upper ends of the vertical members 12^d are extended somewhat above the upper chords of the truss 12^a so that their ends will lie substantially in an arc conforming substantially to the curvature of the crown 11. To the upper ends of the vertical members 12^d are attached the

circular purlins 13, upon which the crown 11 rests when the gas holder is empty or deflated.

The outer ends of the trusses 12 are supported by the gussets 14 attached to the bell. The inner ends of the trusses 12 are attached to a center ring 15; and are somewhat higher than the outer ends.

16 indicates a tower in the center of the holder resting on the bottom.

When the holder is empty, the crown rests on the purlins 13 which are carried by the trusses 12. In this position, the inner ends of such trusses are carried by the tower 16; so that each member 12 acts as a simple truss or beam to carry a part of the weight of the crown.

When the holder is inflated, the trusses 12 rise with the inner lift, leaving the tower and supporting themselves and the circular purlins 13. In this position, their outer ends being rigidly supported by the gussets 14, and their inner ends being attached to the ring 15, they act as arches. That is, each of such trusses acts with the one diametrically opposite it to form a self-supporting arch. By means of this arch construction, the weight of the trusses and purlins is thus carried when the tank is inflated.

By the use of my invention, radial members, or trusses of like construction, may be used for the distance which each spans is only one-half of the diameter of the gas holder when the same is deflated and the load of the crown is resting on such trusses.

It is to be noted that the crown plates 90 are not fastened to the purlins 13. By this construction considerable expense is saved.

In addition to the above, it is to be noted that the trusses are not fastened to the tower 16 but their inner ends merely rest upon the same when the tank is deflated. The tower does not rise and fall with the inner lift as is true of some crown supports heretofore in use. Thus doing away with the lifting of the tower simplifies and cheapens the construction. In this connection, it is to be noted also that there is another great advantage in not fastening the trusses to the tower. By such construction, the tower may be used to assist in the erection of the holder. In those constructions of crown supports, where the tower is carried up and down with the inner lift, it must be built

as an integral part of the crown support. In such cases it cannot be used in connection with the erection of the structure.

In general, it might be stated, that one of the principal features of my invention is the provision of a crown support system which supports itself by arch action when the holder is inflated and there is no load; but which is so constructed that it has sufficient strength to support the crown and loads which might be on the crown when the holder is empty.

While I have shown and described certain embodiments of my invention, it is to be understood that it is capable of many modifications. Changes, therefore, in the construction and arrangement may be made without departing from the spirit and scope of the invention as disclosed in the appended claims, in which it is my intention to claim all novelty inherent in my invention as broadly as possible in view of the prior art.

What I claim as new, and desire to secure by Letters Patent, is:

25. 1. In a gas holder of the character described, having an inner bell with a crown, a crown support comprising; a plurality of radial trusses arranged beneath the crown of the inner bell, the outer ends of said trusses being attached to said inner bell, the inner ends of said trusses being higher than the outer ends thereof and fastened together, whereby said trusses will form a self-supporting arch construction which will rise and fall with the inner bell; and a centrally arranged tower inside of said gas holder adapted to support the inner ends of said trusses when the gas holder is deflated whereby said trusses will then carry the weight of the crown.

40. 2. In a gas holder of the character described, having an inner bell with a crown, a crown support comprising; a plurality of radial trusses arranged beneath the crown of the inner bell, having their outer ends connected to said bell, their inner ends somewhat higher than the outer ends and joined together to form a self-supporting arch construction, said trusses not being directly connected to said crown; and a centrally arranged tower in said gas holder adapted to support the inner ends of said trusses when the gas holder is deflated whereby said trusses will then support said crown.

45. 3. In a gas holder of the character described, having an inner bell with a crown, a crown support comprising; a plurality of radial trusses arranged beneath the crown of the inner bell and carrying crown supporting members, the outer ends of said trusses being connected to said bell, and the inner ends being higher than the outer

ends and joined together to form a self-supporting arch construction; and a centrally arranged tower in said gas holder adapted to support the inner ends of said trusses when the gas holder is deflated whereby the crown supporting members carried by the trusses will then carry the weight of the crown.

7. 4. In a gas holder of the character described, having an inner bell with a crown, a crown support comprising; a plurality of radial trusses arranged beneath the crown of the inner bell, the outer ends of said trusses being attached to said inner bell, the inner ends of said trusses being higher than the outer ends thereof and fastened together by a ring member, whereby said trusses will form a self-supporting arch construction which will rise and fall with the inner bell; and a centrally arranged tower inside of said gas holder adapted to support the inner ends of said trusses when the gas holder is deflated whereby said trusses will then carry the weight of the crown.

8. 5. In a gas holder of the character described, having an inner bell with a crown, a crown support comprising; a plurality of radial trusses arranged beneath the crown of the inner bell and carrying crown supporting circular purlins, the outer ends of said trusses being connected to said bell, and the inner ends being higher than the outer ends and joined together to form a self-supporting arch construction; and a centrally arranged tower in said gas holder adapted to support the inner ends of said trusses when the gas holder is deflated whereby the crown supporting circular purlins carried by the trusses will then carry the weight of the crown.

10. 6. In a gas holder of the character described, having an inner bell with a crown, a crown support comprising; a centrally arranged tower in the center of the gas holder adapted for use as erection equipment in the construction of the gas holder; a plurality of radial trusses arranged beneath the crown of the inner bell and having their outer ends attached to said bell, the inner ends of said trusses being higher than the outer ends and joined together to form a self-supporting arch construction, the inner ends of said trusses also adapted to rest on said tower when the gas holder is deflated whereby said trusses will then carry the weight of said crown.

11. In testimony whereof, I have hereunto set my hand this 14th day of Sept., A. D. 1925.

AUBREY W. SEELS.
